UNITED STATES PATENT OFFICE

FELIX W. TEACHOUT, OF HUNTINGDON, TENNESSEE

DISPLAY RACK

Application filed January 19, 1929. Serial No. 333,595.

The present invention relates to improvements in display racks and more particularly to a rack for displaying overalls and trousers so that the various sizes may be arranged accordingly and, therefore, can be more easily located and removed, and after removal, when necessary, may be more easily placed in the pile within the rack, said rack being mounted so as to revolve upon a vertical axis so that the various sizes may be brought into view by merely rotating the rack.

Another object of this invention is the provision of a rack of this type which may be placed within a cabinet so as to prevent the dust and dirt from affecting the saleable goods and which can be readily operated by the salesman to bring into ready access the desired article without disturbing those of a different size or character.

With the foregoing and other objects in view, which will appear as the description proceeds, the invention resides in the combination and arrangements of parts and in the details of construction hereinafter described and claimed, it being understood that changes in the precise embodiment of the invention herein disclosed can be made within the scope of what is claimed without departing from the spirit of the invention.

In the drawings:—

Figure 1 is a perspective view of the complete rack, portions of which are shown merely in skeleton to illustrate the structure more clearly.

Figure 2 is a vertical cross-section through the supporting column and pedestal and adjacent portions of the rack.

Figure 3 is a section taken on line 3—3 of Figure 2.

Figure 4 is a section on line 4—4 of Figure 2.

Figure 5 is a section on line 5—5 of Figure 4.

Figure 6 is a perspective view of one of the shelves per se.

Referring to the drawings, the numeral 10 designates the pedestal or base which is adapted to be secured to the floor or main supporting member and has mounted therein the rotatable spindle 11 whose head 12 is seated in

the hollow lower end of the pedestal. A ball bearing 13 is disposed between the head 12 of the spindle and the adjacent portion of the pedestal. The spindle 11 is provided with external screw threads adjacent its upper end and a ball ring 14 and lock nut 14' are mounted on said threaded portion for properly adjusting the upper ball-bearing 15. By this means, the spindle 11 is supported by anti-frictional means so that it may be rotated with the least possible effort. A vertical tubular column or support 16 has its lower end internally threaded to receive the threaded upper end of the spindle 11 and a lock screw 17' carried by said support and engaging the spindle 11 serves to lock the support in adjusted position on the spindle, while the upper end of the support 16 is exteriorly threaded, as at 18, the purpose of which will presently appear.

Mounted on the tubular support 16 adjacent the lower end thereof is a bar 17 which is made from an angle-iron and is provided with the aperture 19 to fit upon the tubular support 16 and be attached thereto by means of the set-screw 20, while on the upper end of said tubular support 16 is an upper bar 21 having the interiorly threaded opening 22 which engages the upper externally threaded end 18 of the tubular support and is held against independent movement thereon by means of the set-screw 23. The bars 17 and 21 are, therefore, disposed in parallel relation to each other and extend in opposite directions from the support 16 so as to provide the main supporting means of the present rack, and braces 6 extend between the support 16 and the under side of the bar 21 at opposite sides of the support.

As shown, there are four transverse frames 24, 24' and 25, 25', the frames 24 and 24' being alike while the frames 25 and 25' are also alike. The frames 24 and 24' constitute the end frames, while the frames 25 and 25' constitute the intermediate frames. Each end frame comprises a pair of bars 26 and 26' connected, respectively, approximately midway between their ends to the extreme ends of the bars 21 and 17 and at right angles thereto, these bars 26 and 26' being slightly

curved in cross-section and being connected adjacent their ends by vertical strips 28 and adjacent their points of connection to the bars 17 and 21 by pairs of vertical strips 28'.
5 Elongated offset cuts or openings 29 are formed in the strips 28 and 28', the purpose of which will presently appear. The frames 25 and 25' each consists of a pair of parallel horizontal bars 30 and 31 which are attached, 10 respectively, approximately midway between their ends to the bars 21 and 17, as at 32, between the frames 24 and 24' and the support 16. The bars 30 and 31 are curved in cross-section and are similar to the bars 26 and 26'.
15 The bars 30 and 31 are connected at their ends by pairs of spaced vertical strips 33 and are connected adjacent their points of connection to the bars 17 and 20 by two spaced pairs of spaced vertical strips 33. Offset cuts or openings 34 are formed in the strips 33 and 33' similar to and spaced apart the same distances as the cuts or openings in the strips 28 and 28'. It will thus be seen that the bars 17 and 21 carry, in the present instance, 20 four transverse frames and that said frames are arranged in pairs so that a series of 25 shelves can be disposed between and be supported between each adjacent pair of frames and that the offset openings in the strips 28, 28', 33 and 33' form means for supporting shelves 35. Each shelf, as clearly shown in Figure 6, consists of a rectangular piece of metal provided at its corners with downwardly bent terminals or prongs 36 and 36' and adjacent one corner with a tag carrying lug 37 which is cut and bent upwardly from the body of the shelf. Thus, in inserting one 30 of these shelves, it is only necessary to insert the prongs 36' in the offset openings 29 and 34 of a pair of opposed vertical strips 28' and 33' or 33' and 33' the prongs 36 in the offset openings 29 and 34 of a pair of opposed vertical strips 28 and 33 or 33 and 33, it being only necessary to make sure that the shelves 35 are so disposed that their prongs will align with horizontally aligned openings of the strips between which they are inserted to provide a level support for the overalls or trousers.

50 By the above arrangement, the shelves may be placed close together to carry a small number of odd sizes in little demand, or far apart to accommodate a larger number of the sizes in greater demand, and by reason of the 55 fact that each shelf carries an indicating mark, the overalls or trousers of a certain size may be readily located without the necessity of removing a great number, as is the present practice.

60 I claim:—

1. A display rack including a pedestal, a vertical and rotatable support carried thereby, two bars attached to and carried by said support and extending in opposite directions therefrom, a plurality of frames attached to

said supports and in spaced relation, each of which frames is provided with a pair of perforated strips, and a plurality of shelves for disposition between said strips.

2. A display rack including a pedestal, a 70 rotatably and vertically mounted support carried thereby, a pair of bars attached centrally of their lengths to said vertical support adjacent the upper and lower ends of the latter respectively, and disposed in parallel relation to each other, a plurality of pairs of parallel bars extending transversely of and fixedly secured between their ends to the first bars on each side of the vertical support, and a plurality of shelf-supporting 75 strips connecting each pair of said transverse bars.

3. A display rack including a pedestal, a rotatably and vertically mounted support carried thereby, two bars attached centrally 80 of their lengths to said vertical support and disposed in parallel relation to each other, a plurality of pairs of transverse bars attached to the first bars and upon opposite sides of the vertical support, a plurality of 85 shelf-supporting strips connecting each pair of said transverse bars, each of said strips being provided with perforations, and a plurality of shelves each of which is provided at each of its corners with a prong insertible in one of said perforations.

In testimony whereof I have hereunto set my hand.

FELIX W. TEACHOUT.
